UNITED STATES PATENT OFFICE.

ALFRED ATTENBOROUGH, OF BRISTOL, CONNECTICUT, ASSIGNOR TO THE BLAKESLEY NOVELTY COMPANY, OF BRISTOL, CONNECTICUT, A CORPORATION OF CONNECTICUT.

BRAIDING-MACHINE.

No. 861,694.

Specification of Letters Patent.

Patented July 30, 1907.

Application filed April 10, 1905. Serial No. 264,665.

To all whom it may concern:

Be it known that I, ALFRED ATTENBOROUGH, a subject of the King of Great Britain and Ireland, residing at Bristol, in the county of Hartford and State of Connecticut, have invented certain new and useful Improvements in Braiding-Machines; and I do hereby declare the following to be a full, clear, and exact description of the invention, such as will enable others skilled in the art to which it appertains to make and use the same.

The present invention relates to braiding machines and more particularly to braiding machines designed for producing lace fabrics and which are generally known as lace braiding machines.

As is generally known to those skilled in this art these machines comprise a series of spindles upon which are mounted the thread carrying bobbins, which spindles are by suitable mechanism caused to move in a generally circular path about a core or mandrel and to cross and re-cross each other's path, thus laying their threads about the core or mandrel, and in the case of machines for making lace the movements of the spindles are controlled by a pattern mechanism whereby they cross and re-cross the threads about the core or mandrel in a predetermined manner to produce the desired pattern of lace.

The objects of the present invention are generally to greatly simplify the construction and mode of operation of the machine, and particularly the supporting, guiding and operating mechanism for the spindles, the beaters and their operating mechanism and other parts of the machine, all as will hereinafter appear.

To the above ends the present invention consists of the devices and combinations of devices which will be hereinafter described and claimed.

The present invention is illustrated in the accompanying drawings in which:

Figure 1 shows a top plan view of a machine embodying the same. Fig. 2 shows on a larger scale than Fig. 1, a vertical sectional view, with some parts in elevation, and some parts omitted for clearness. Fig. 3 shows on a still larger scale an elevation of a portion of the operating mechanism for the spindles. Fig. 4 shows a plan view of a portion of the spindle supporting and operating mechanism. Fig. 5 shows in cross section a portion of the spindle supporting and operating mechanism. Fig. 6 shows in top plan view (portions broken off) one of the spindle switches. Fig. 7 shows the same parts as shown in Fig. 6, looking at the point of the switch. Fig. 8 shows in side elevation one of the latches which holds the spindles at rest and out of engagement with their operating mechanism. Fig. 9 shows in side elevation and

partial section the guide for the traveling core or mandrel, the beater plate and cam and the beater elements. Fig. 10 shows an underside of the beater cam. Fig. 11 shows a top plan of the beater plate. Fig. 12 shows in side elevation in full lines one of the long shank beaters, and in dotted lines a similar beater having a short shank. Fig. 13 shows a rear end elevation of a beater. Fig. 14 (Sheet 1) shows the beater guide plate. Fig. 15 shows in elevation and partial section a spindle with a threaded bobbin mounted thereon. Fig. 16 shows a top plan view with a portion of the upper end of the spindle broken away. Fig. 17 shows a diagrammatical plan of the operating gearing for the spindle and beater mechanism. Fig. 18 is a plan of a fragmentary portion of the spindle mechanism. Figs. 19 and 20 show top plan views of the spindles supporting and guiding plates and illustrating diagrammatically the movement of the spindles.

Similar reference characters will be employed throughout the specification and drawings to designate corresponding parts.

The machine comprises a frame of suitable size and shape to support the operating parts, that shown embodying a top plate 1, mounted upon the legs or standards 2, the latter also supporting and being braced by a second or under plate 3, and the two plates being provided with the central openings 4 and 5 connected by 80 the guide tube 6, all as clearly shown in Fig. 2.

Mounted upon the top plate 1 in a circular line concentric with the axis of the guiding tube 6 are the vertical posts 7 held to said plate 1 by the nuts 8 (see Figs. 3 and 6), and upon said posts are mounted to turn the sleeves 9 carrying near their lower ends the gears 10, the adjacent gears meshing with each other, all as clearly shown in Fig. 17 whereby the adjacent sleeves will be driven in opposite directions, as will be clearly apparent from an inspection of Fig. 17. There are in 90 the machine of the drawing twenty-eight of these geared sleeves which as shown form a complete geared ring, the adjacent members of which will be driven in opposite direction with relation to each other. Motion is imparted to these geared sleeves 9 from the main shaft 11 mounted to turn in bearings 12 below the top plate 1, the said shaft carrying a bevelled pinion 13 which meshes with and drives a bevelled pinion 14 carried upon the lower end of a stub shaft 15 mounted in a bearing 16 in the top plate 1, and which above said top plate carries a pinion 17 which meshes with and drives one of the geared sleeves 9, which in turn imparts a rotary movement to the entire ring of geared sleeves. (See Figs. 2 and 17.) The main shaft is provided at one end with suitable driving pulleys 18 and at its 105 opposite end with a hand wheel 19.

The upper ends of the posts 7 are provided with the fixed guiding and supporting disks 20 and the upper ends of the above 2 with the driving translating disks 21 of such a diameter that the peripheral edges of adjacent disks 21 will closely approximate each other, and each of the disks 21 is provided with the diametrically disposed notches 22, the notches in one disk 21 being so disposed with relation to the notches in the next adjacent disk upon each side as to register therewith when the disks are revolved, as clearly shown in Figs. 19 and 20, and form a space to receive the stems of the spindles to cause a translation of the spindles in a manner well known to those skilled in this art. The stems of the spindles can pass freely between the supporting disk 20, but can only be passed between the disks 21 when engaged in the mating notches 22 of adjacent disks, all as will be clear from an examination of the drawings.

The spindles as shown in Fig. 15 are provided with a stem 23 and two disks or collars of uniform diameter 23 and 24, the collar 24 when the spindles are in the machine being received between the fixed disks 20 of the posts 7 and the movable disks 21, and the collar 23 resting upon the upper surface of the disks 20 and upon the supporting rings or plates 25 and 26. (See Figs. 3 and 4.)

The supporting plates or rings 25 and 26 are mounted upon posts 27 projecting upward from the top plate 1, and as shown in Figs. 4, 19 and 20, said plates are circular in form and their inner opposing edges are cut out as at 28 forming a series of curved arcs struck from the axis of the posts 7 as the centers, and when in position leaving sufficient space between said plates 25 and 26 and the disks 20 for the free movement of the stems 23 of the spindles, which as is well known to those skilled in this art must have a circular movement around the central core or mandrel and also about the axis of the posts 7 in order to properly cross the threads and lay them about the core or mandrel in making the lace.

In the machine of the present invention the plates 25 and 26 or rather the curved arcs 28 and the intervening points 29, do not in any manner guide or control the movements of the spindles and bobbins, as an inspection of Figs. 19 and 20 will show that the space between the driving disks 21 and the curved edges of the plates 25 and 26 is greater than the diameter of the stems 23 of the spindles; but said plates 25 and 26 merely aid in supporting by the collars 23, the spindles, which collars rest upon and travel over said plates and the disks 20 of the posts 7. The result is that when the driving disks 21 move a spindle to the point indicated by "a", in Fig. 20, it may there remain at rest unless and until it is again put in position to be engaged by the driving disks, by the arms of the switches, which inasmuch as they force or project the spindles which may be at rest into the notches of the driving disks will be hereinafter called projectors and which, and the switches will be hereinafter described. The spindles and bobbins are however guided by guide rings or plates 30 and 31 which are supported beneath the plates 25 and 26 respectively and which like said plates are provided upon their opposing inner edges with the curved arcs 32 struck from the same centers as the curved arcs 28 but on greater radii, so that

their edges will lie inside of the edges of the plates 25 and 26 in position to engage the guiding collar 24 of the spindles against which said collars bear as the spindles are carried around. (See Figs. 4, 5, 19, and 20.)

From the foregoing description it will be noted that the driving shaft imparts a constant rotation to the driving disks 21, which by means of the notches 22 engage the stems of the spindles and cause them to travel around the core or mandrel as a center and to change position with relation to each other by traveling about the axes of the posts 7, and that this travel of the spindles and bobbins when guided by the guides 30 and 31, and controlled by the mechanism which will next be described, will cause the threads to be crossed and recrossed about each other and laid about the core or mandrel in such a manner as to produce lace of any desired pattern, the spindles in their movements being supported by the plates 25 and 26 and the disks 20 and guided by the plates 30 and 31.

It will be noted that the spindles are moved radially back and forth between the edges of the plates 25 and 26 and while thus moving they are held and guided by the mating notches 22 in adjacent driving disks 21 and while being so moved they are supported upon the disks 20, but that while moving around from one side of a driving disk to the other the movement is impeded by the notch of one disk only, the stem of the spindle during this movement being held in engagement with the notch of the driving disk by the engagement of the guiding collar 24 with one of the guiding plates 30 or 31.

The direction of the movement of the spindle is controlled by a series of switches 33 (see Figs. 4, 5, 6 and 7), which are thin plates of metal with curved sides 34 and 35, the arcs of which intersect and form the points 36 and the curves being on arcs parallel to the peripheries of the disks 20 and 21. These switches 33 are mounted upon blocks 37 pivotally mounted by means of studs 38 upon the upper surface of the plates 25 and 26. There are twenty-eight of these switches, fourteen upon each side of the line of driving disks 21, and as shown in Figs. 1 and 4, those switches upon one side are arranged alternately with those upon the other side, the points 36 of the switches projecting into the space between adjacent driving disks 21 and in the direction to meet the on-coming spindle, that is to say, the switches point in the opposite direction to the direction of movement of the opposing surfaces of the driving disks between which they are located. The switches are arranged to be shifted about the pivots 38 for the purpose of meeting and changing the direction of movement of the on-coming spindles and those upon either side are all moved simultaneously and in unison with each other, but the opposing groups are alternately shifted in opposite directions. For the purpose of shifting the switches 33 each of the blocks 37 supports a plate 39, held thereto by a screw 40 and which at its rear end is provided with a notch or recess which takes over and engages an eccentric 42 adjustably secured by means of screws 43 to a ring or carrier 44 mounted upon the upper surfaces of the plates or rings 25 and 26 and free to have a reciprocating rotation for a limited distance. Thus by the movement of the

eccentric 42 the plates 39 are moved in a circular path and the switches 33 are shifted in opposite directions, so as to meet the on-coming spindles and project them into the notches of the driving disks 21.

5 rings 44 the entire group of switches are shifted, and as the rings 44 are moved simultaneously back and forth in opposite directions, it follows that the entire group of switches on one side of the line of driving disks 21 will be shifted in one direction while the group on the opposite side will be shifted in the opposite direction. The eccentric studs 42 may be turned more or less about the screws 43 to secure the proper adjustment of the plates 39 with the operating rings 44, and 10 will be understood. The rings 44 are reciprocated (see Figs. 1, 17 and 18) by means of links 45 pivotally connected at 46 to said rings and at 47 to slides mounted adjustably upon disks 48, one of the disks 48 (see Figs. 17 and 18) being secured to a gear 49 driven 15 through an intermediate gear 50 from one of the gears 10, and the other of said disks 48 being mounted upon a gear 51 driven through an intermediate gear 52 from one of the gears 10.

It will be noted by an inspection of Fig. 4 that the 20 switches 33 are interposed in each alternate space between the revolving driving disks 21 on each side of the line of disks, so that a switch will be interposed between each pair of such revolving driving disks 21 and pointing in a direction opposite to the direction of travel of the adjacent surfaces of such driving disks. Thus it will be noted that the surfaces of the disks 21 between which the points of the outer line of switches are interposed will be traveling in the direction of the 25 arrows X shown in Fig. 4, and that the surfaces of the driving disks 21 adjacent to the points of the inner line of switches will be traveling in the direction as indicated by the arrows X', Fig. 4, so that the points of the switches will be interposed between and point in the direction opposite to that in which the revolving disks 30 21 are carrying the spindles, and as the points of the switches are deflected either to the right or left will be determined the direction of travel of the spindles, whether such spindles shall travel around a revolving disk to the right, or shall travel around a revolving 35 disk to the left, all of which will be clear it is thought from an inspection of Fig. 4 of the drawing.

It will be understood to those familiar with this art that the spindles are not all of them at all times in motion and that in producing the desired pattern of lace 40 45 some of the spindles are held at rest, while others are in movement and the points at which they are held at rest are at the points between adjacent switches, as clearly shown in Fig. 4 of the drawing, where s indicates two of the spindles at points of rest and s' indicates two of the spindles in movement, the line of movement as indicated by the arrow x' being such as to carry the upper spindle s' as the parts are illustrated in Fig. 4, to the right and the lower spindle s' to the left, it being understood that the spindles move in pairs around the axes of 50 55 the points 7.

For the purpose of holding the spindles stationary at the points of rest, there are provided suitable latches arranged to engage the lower part 22 of the stem of the spindle. One of these latches 53 is shown in side elevation in Fig. 8, and a portion of the base of one of the latches is shown in Fig. 3, and in Fig. 4, one of them is shown in top plan view and the other indicated by dotted lines.

As shown at Fig. 8, the latches 53 consist of suitable

standards 54 which are secured on the top plate 1 by 55 means of screws 55 passing through apertured lugs formed integrally with the standards 54. The latch proper 56 is provided with a shank 57 received in a recess in the standard 54 and pivoted therein by means of a pin 58 whereby the latch proper 56 may have a swing- 70 ing movement to a slight extent up and down whereby to permit the passage of the stem of the spindle over said latch when it is not intended that the spindle shall be held, and also for the purpose of releasing the stem of the spindle when it is desired to again place said 75 spindle in operation.

The latch 56 is normally held upward by a light spring 59 received in a bearing 60 formed in the standard 54 and bearing against the under side of the latch 56. The upper surface of the latch 56 is provided with 80 a curved groove 61 and a notch or seat 62 (see Fig. 4), and the forward surface is beveled as shown at 63. The arrangement is such that as the spindles are moved by the driving disks they will, when they reach one of the latches engage the inclined surface 63 by the end of the 85 stem 22* and depressing the latch proper 56 slightly, which will by means of its spring be again raised to engage the stem of the spindle and hold said spindle at rest, and there it will remain at rest held by the latch until it is disengaged therefrom and again started in 90 motion. This disengagement of the spindles from the latches is produced by the wings which I have heretofore referred to as projectors 64, two of such projectors being carried by each of the latches 33, and as shown in Figs. 4, 5, 6 and 7 these projectors are pivoted by 95 means of rounded heads 65 between the plate 39 and the block 37, they being held firmly in place, but so as to have a free up and down movement by means of a yoke 66 and the plate 39, which as before stated is held to the block 37 by the screw 40.

The projectors 64 are normally held in a horizontal plane by means of light coiled springs 67 (see Figs. 3, 4 and 5), which engage upwardly projecting studs 68 carried by the projectors 64. The yoke 66 acts as a stop to limit the upward movement of the projectors 64. It 100 will be understood that these projectors are mounted upon the blocks 37 and therefore partake of the pivotal action imparted to the switches about the pivots 38 by the circular reciprocating rings 44, and the rounded top 69 of these projectors when the projectors are depressed 105 as shown in Fig. 3 will when they are swung about the pivots 38 come in contact with the collar 23 of the spindles and will thereby force the stem 22* of the spindle out of the latch 56 and project said spindle forward 110 towards the axial line of the driving disks 21 and into position to be engaged by the mating notches of said driving disks and thus be put in motion. It will of course be understood that it is the operation of these projectors and switches which determines the pattern produced by the movement of the spindles and that therefore the 115 downward depression of the projectors of any given pair of switches takes place simultaneously as shown in Fig. 3 of the drawing, and in such time relation to the movement of the spindles as to cause the projection into operation of those spindles which may be at rest at the desired time, and it will be further understood that unless the projectors 64 are depressed so as to engage the collar 23 of a spindle the rocking movement of the 120 125

switches will simply control the direction of movement of those spindles which may be in operation and will pass over without engaging the collars of those spindles which may be at rest, so that all of the spindles may be operated to cause them to move about the mandrel or core, and about each other and remain at rest, all in proper time relation so as to produce the proper crossing and re-crossing of the threads of the various spindles as they are laid about the core or mandrel.

10 The projectors 64 are depressed by means of the wires 70, one connected to each of the projectors 64, and passing down through openings 71 and 72 in the plates or rings 25 and 26 and 30 and 31, and through openings 73 in the top plate 1, and are connected at 15 their lower ends to a series of levers 74, said levers being of suitable length as shown in Fig. 2 and being pivoted as at 75 to brackets or standards mounted upon the lower plate 3 of the frame and said levers are rocked in suitable time relation to depress the desired projectors 64 by means of a plurality of two- 20 armed levers 76 pivoted at 77 to a frame or bracket 78, one arm of said levers being connected by means of wires 79 to the levers 74 and the other arm of said levers 76 being provided with tappets 80 arranged to 25 be engaged by projecting rollers or studs carried by a suitable pattern or jacquard mechanism 81, which may be formed in the shape of a cylinder as shown in full lines in Fig. 2, or in the form of a chain comprising segmental sections as shown in dotted lines in 30 Fig. 2.

It will be understood by those familiar with this art that the pattern or jacquard mechanism 81 is provided with studs or rollers which are spaced at suitable points along its surface to engage and rock the two-armed levers 76 in proper time relation to each other, whereby through the rods 79 and the levers 74 to depress the projectors 64 to control the operation of the spindles, and that by changing the form and arrangement of the studs or rollers of the 40 pattern or jacquard mechanism so as to operate the projectors in varying and different time relations to each other, any desired sequence of operation of the spindles may be produced in order to produce any desired pattern of lace.

45 The pattern or jacquard mechanism in and of itself forms no part of my invention and as the operation of such mechanism is well understood to those familiar with this art, it is deemed unnecessary to further explain the same. It is of course understood that this 50 pattern or jacquard mechanism has a continuous revolving motion and for this purpose it is operated by a wheel 82 mounted upon a shaft 83 held to revolve in suitable bearings in the frame 1 and carries a worm wheel 84 which meshes with and is driven by a worm 55 85 on the main shaft 11.

The spindles travel around and lay their threads upon a mandrel which mandrel may be of any usual or preferred construction, that shown in the drawing, however, being a traveling mandrel and the machine 60 is particularly designed for use with such a mandrel, and it is preferred to use a traveling mandrel such as shown. This mandrel 86 consists of an endless flexible core which may be formed of rubber or other suitable material and it is supported upon a wheel 87 mount-

ed to turn upon an axle 88 supported in a bracket or 65 frame 89 (see dotted lines, Fig. 2 and full lines Fig. 1), fastened to a cross piece 90 supported by uprights from the top plate 1, and passing over guide pulleys 91 and 92 and up through the guide tube 6, and a hollow sleeve 93 supporting the beater mechanism. 70 The mandrel 86 also passes through a guide 94 at the lower end of which the threads are laid about the mandrel, this guide 94 being supported by a plate 95 suspended by means of bolts 96 (see Fig. 9), from the cross piece 90, and thence through an aperture 75 or bearing 97 in said cross piece 90 and up between a pair of grooved feeding rolls 98 by means of which the core or mandrel 86 is drawn upwardly through the guide 94 as the lace is formed thereon.

The feed rolls 98 are mounted upon shafts held to 80 rotate in suitable bearings 99 supported upon the cross piece 90 and are revolved in opposite directions by means of the gears 100 meshing with each other, and a beveled gear 101 meshing with and driven by a beveled gear 102 secured to one end of a horizontal 85 shaft 103 mounted to rotate in suitable bearings 104 supported by brackets 105 mounted upon the upper surface of a cross piece 106 supported by a vertical stand 107 upon the top plate 1, the shaft 103 being driven by a worm wheel 108 meshing with a worm 90 109 at the upper end of the vertical shaft 110, which shaft at its lower end carries a pinion 111, which by means of the train of gears 112 is driven from the main shaft 11.

As is well known to those skilled in this art, the 95 crossed threads must be laid upon the core or mandrel with the point of crossing laid closely up to the points of previous crossings; that is to say, close to the end of the finished product as the lace is formed, and for this purpose there are employed thin fingers of metal 100 known as beaters which enter between the two threads back of the point of crossing and moving towards the mandrel force the point of crossing close up to the completed fabric.

The beaters in the present machine are shown clearly 105 in Fig. 2 in operative position and in Figs. 12 and 13 one such beater is shown in detail removed from the machine and the beater operating mechanism is clearly shown in Figs. 9, 10, 11 and 14. As shown in Figs. 12 and 13, the beaters comprise the upwardly extending 110 thin fingers 113 formed integrally with the shanks 114 extending at right angles to the beater fingers 113. There are two groups of beaters, one group having a long shank 114, as shown in full lines in Fig. 12, and the other group having shorter shanks, as indicated by 115 the dotted lines 115, in Fig. 12, and each of the beaters has upon its shank 114 an upwardly projecting toe 116, located near the end of the shank. These beaters, there being twenty-eight in the machine of the drawing, are supported in radial grooves 117 formed in the, 120 upper surface of the beater plate 118 which is fixedly supported upon the upper end of the tubular stand 93, all as clearly shown in Fig. 2 of the drawing, and the beaters are arranged in their grooves 117 in alternate rotation; that is to say, a short shank beater between two adjacent long shank beaters. In operation, these beaters have a horizontal movement radially toward and from the mandrel 86 and this movement is 125

5 impeded by the beater cam shown in Fig. 10, which cam has two cam paths 119 and 120, inversely arranged with relation to each other, the cam path 119 being arranged to receive the upwardly projecting toes 116 of the long shank beaters and the cam path 120 to receive the upwardly projecting toes of the short shank beaters, and when said cam is in position as shown in Fig. 2, a revolution thereof will by means of the cam paths 119 and 120 cause the beater shanks to move radially in their grooves 117 and thus move the beater fingers 113 towards and from the mandrel.

10 The beater cam is arranged to be continuously rotated in suitable time relation to the operation of the other parts of the machine, and from an inspection of Fig. 10 it will be noted that the beaters at diametrically opposite points are simultaneously and progressively moved in opposite directions, so that one group of beater fingers 113 will be progressively advanced towards the mandrel while on the opposite side they are 15 being progressively withdrawn from the mandrel. The beater cam is mounted above the beater plate 118 and is revolved by the upwardly projecting finger 121, engaging a projection 122 at the periphery of said beater cam, and said finger 121 is carried by a plate or 20 disk 123 forming the top plate of a revolving frame comprising also the gear ring 124 and the connecting rods 125 connecting the ring 123 and the gear ring 124. The gear ring 124 meshes with and is driven by the pinion 126 which in turn is driven by a gear 127 which 25 in turn is driven by a pinion 128, which in turn is driven by a large gear 129 (see Fig. 17 of the drawing). At various points about the gear 129 may be introduced the idle gears 130 and 131 meshing respectively 30 with the gear 129 and with the chain of gears 10, whereby the driving of the gears will be properly balanced.

35 The beater fingers 113 being quite thin must be properly supported in order to prevent springing, and for this purpose there is provided a beater guide plate 132, shown in Fig. 14, provided with the interior opening 133 and the radial slots 134, into which the upper ends of the beater fingers 113 are fitted and arranged, to slide, and the plate 132 is supported upon standards 135 from the beater plate 118 a suitable distance above 40 the beater plate and below the mandrel guide 94, leaving sufficient space 136 between said beater guide 45 and the mandrel guide 94 for the threads to be laid against the mandrel.

50 In order that the threads leading from the bobbins may clear the beaters, or rather that the beaters may clear the threads, upon the return or outward movement of the beaters, there are provided the thread lifters 137 (see Figs. 2 and 9), which are in the form of curved plates having the curved edges 138 which for 55 a portion of their length are of a height to clear the upper ends of the beater fingers 113. These thread lifters 137 are fastened by means of screws 139 to the upper surface of the beater cam and revolve therewith and are so placed on said cam with relation to the beater operating cam grooves that the high parts 138 of the thread lifters will come under and lift the threads as the beaters are withdrawn by the beater cam. This insures a free action of the beaters without any liability 60 of their entanglement upon their return movement.

65 with the threads leading to the bobbins. There will also be provided a suitable guard ring 140 which may be supported in any suitable manner and upon which the threads rest as they lead from the bobbin to the mandrel. Any suitable form of spindle may be employed, that shown in the drawings comprising a cylindrical tube 141 (see Fig. 15 of the drawing), upon which is placed and fitted a collar 142 carrying an upwardly extending thread guide 143 provided with the thread eyes 144 and 145 and upon this tubular sleeve 141 is arranged to be received and to freely turn 70 thereon the bobbin 146 provided with thread 147. Within the tubular sleeve 141 is held a coiled spring 148 which carries a thread eye 149. The thread leads from the bobbin through the eye 144, thence through the eye 145 and thence through an eye 150 of a pivoted 75 detent 151, and thence through the eye 149 carried by the spring 148, and then out through a capped bearing 152 inserted in the upper end of the tubular sleeve 141. The detent 151 engages with notches 153 cut in the upper end of the bobbin and the tension of the 80 spring 148 is sufficient to keep the thread taut from the mandrel to the spindle and to prevent the turning of the bobbin on the tubular sleeve 141 until sufficient draft is placed upon the thread leading to the mandrel, so as to extend the spring 148 until the eye 85 or ring 149 comes in contact with the end of the detent 151 and lifts said detent from the notch of the bobbin in which it may be engaged, thus permitting the bobbin to turn another notch to give up thread, after which the detent will again be drawn into engagement with one of the notches and the slack of the 90 thread taken up by the spring 148, all in a manner well known to those familiar with these machines.

95 It is of course understood that each of the spindles carries a bobbin of thread and that by their movements around the core or mandrel and their crossing and re-crossing movements the lace fabric is formed. It is further understood that while the lace fabric is formed in tubular form, it is in fact when removed from the mandrel a strip of lace having two selvage edges 100 which selvage edges are united by a false thread, the false thread being cut as the strip of lace fabric is removed from the core or mandrel. In the machine of the drawing this false thread which is lettered *t* (see Figs. 3 and 4) is led from a spool supported beneath the 105 top plate 1, (not shown in the drawings) and is led up through one of the posts 7 which is made hollow for this purpose, and thence up through a guide tube *t* projecting upward from the axis of one of the revolving disks 21, the arrangement being such that the crossing 110 and re-crossing of the spindle threads with this false thread *t* causes the false thread to unite in a zig-zag manner the selvage edges of the strip of material.

115 The operation of my invention is as follows:—Supposing the various spindles to be provided with thread 120 carrying bobbins and the machine provided with the desired pattern or jacquard mechanism to produce a particular design or pattern of lace, when the main shaft 11 is set in operation it will at once through the worm 25 and worm wheel 21 start the pattern or jacquard mechanism in motion and also through the bevelled pinions 13 and 14 and the gear 17 impart a rotary motion to the ring of gears 10, thus causing the spindles 125

to be thrown into operation by the projectors 64, and causing them to be engaged by the notched disks 21 which carry them in a generally circular path about the core or mandrel, and which spindles by means of the switches 53 are controlled and deflected and caused to travel in one direction or the other about the axes of the ports 7. The switches are constantly reciprocated or oscillated from one side or the other by means of the reciprocating movement of the rings 44 and will 10 be interposed in the path of movement of the on-coming spindles to guide and deflect said spindles to one side or the other, causing a crisscross and re-crossing of the threads. The latches 56 will hold the spindles at rest as they reach the point indicated by the letter *a* in Fig. 20 until they are released from the latches by 15 the engagment of the depressed projectors with the collars 23 of the stem of the spindle. The depression of the projectors is caused in suitable time relation by the pattern mechanism and the interposed levers and rods, and when depressed and oscillated they will engage and project into the path of operation of the notched disks 21 and the spindles which may be at rest. If the projectors are not depressed the oscillation of the switches and projectors will not affect those 25 spindles which may be at rest.

It is of course understood that at the beginning of the operation all of the threads from the spindles and bobbins will be led to and secured to the core or mandrel 56 and as the machine is started in operation this 30 core or mandrel is drawn up through the center of the machine and passes down outside of the frame where the false thread may be clipped and the completed fabric removed from the machine. As the spindles are operating the revolution of the frame comprising the disk 123 and the gear ring 124, causes a revolution of the beater cam and the proper operation of the beaters toward and from the core or mandrel radially to engage the crossing of the threads and force the point of crossing closely to the previous points of crossing of 40 the threads or up to the point of the completion of the fabric.

Having described my invention I claim as new and desire to protect by Letters Patent of the United States:—

- 45 1. In a braiding machine, in combination, a plurality of spindles, a support therefor, a collar on said spindles resting upon the support, a second collar on said spindles arranged beneath the support and a guide located beneath the support and having its guiding surface located within 50 and parallel to the edge of the support against which the spindle collars beneath the support are arranged to bear for guiding the spindles, substantially as described.
2. In a braiding machine, in combination, a plurality of spindles, a support therefor, comprising the supporting 55 rings or plates having the opposing arc-shaped peripheries, and the interposed fixed disks, a collar on said spindles located beneath the support and the guide for said spindles supported beneath the supporting rings or plates and having arc-shaped peripheries located within and parallel to the arc-shaped peripheries of the supporting rings or plates against which the spindle collars are arranged to bear, substantially as described.
3. In a braiding machine, in combination, a plurality of spindles, a support therefor, means to move said spindles 60 over their support, switches for controlling the direction of movement of said spindles, latches to engage and hold said spindles at a point of rest and projectors carried by said switches operating in time relation to the operation of

the switches to disengage said spindles from the latches, substantially as described. 70

4. In a braiding machine, in combination, a plurality of spindles, a support therefor, translating drivers for the spindles, spindle retaining latches, projectors to release said spindles from said latches and means to move said projectors, substantially as described. 75

5. In a braiding machine, in combination, the oppositely arranged supporting plates, the guides for the spindles carried by the supporting plates, the spindles arranged to contact with said guides and means for moving the spindles over the supporting plates, substantially as described. 80

6. In a braiding machine, in combination, the oppositely arranged supporting plates having curved edges, fixed disks interposed between said plates, spindles provided with collars and resting upon said plates and disks, means to move said spindles over the supporting plates and disks, and guides for the spindles mounted upon the under side of the supporting plates against which said spindles are arranged to bear, substantially as described. 85

7. In a braiding machine, in combination, a plurality of spindles, a support therefor, the circularly arranged translating drivers, pivoted switches arranged upon opposite sides of the line of drivers and interposed between said drivers, projectors carried by said switches and means for moving said projectors into and out of position to engage said spindles, substantially as described. 90

8. In a braiding machine, in combination, a plurality of spindles, a support therefor, the circularly arranged translating drivers for said spindles, the switches arranged upon opposite sides of and interposed between the drivers, projectors carried by said switches and moved thereby and a pattern mechanism operating said projectors in suitable time relation to each other to place them into position to engage and project the spindles, substantially as described. 95

9. In a braiding machine, in combination, a plurality of spindles, a support therefor, the circularly arranged translating drivers, means for engaging and disengaging said spindles and drivers and spring controlled pivoted vertically swinging latches for automatically engaging the stem of the spindles to hold them at rest, substantially as described. 100

10. In a braiding machine, in combination, a plurality of spindles, a core or mandrel, means for driving said spindles, a beater supporting plate and reciprocating sliding beaters radially movable on said plate toward and from said core or mandrel, substantially as described. 105

11. In a braiding machine, in combination, a plurality of spindles, a core or mandrel, means for driving said spindles, a beater supporting plate and reciprocating sliding beaters radially movable on said plate toward and from the core or mandrel and means to progressively advance 120 and retract said beaters at diametrically opposite points, substantially as described.

12. In a braiding machine, in combination, a plurality of spindles, a core or mandrel, means for driving said spindles, beaters movable toward and from said core or mandrel, thread guards, and means to operate said guards to remove the threads from the path of movement of the beaters as said beaters move away from the core or mandrel, substantially as described. 130

13. In a braiding machine, in combination, a radially grooved beater plate, beaters mounted in said grooves, and a beater cam for operating said beaters, substantially as described.

14. In a braiding machine, in combination, a radially grooved beater plate, beaters mounted in said grooves, a 135 beater cam for operating said beaters and a radially slotted guide plate for said beaters, substantially as described.

15. In a braiding machine, in combination, a radially grooved beater plate, long and short shank beaters alternately mounted in said grooves and a beater cam having two oppositely arranged cam grooves for engaging and operating respectively the long and short shank beaters, substantially as described. 140

16. In a braiding machine, in combination, the traveling core or mandrel, the sleeve surrounding said mandrel, the beater plate supported upon the upper end of said sleeve, beaters supported by said beater plate the revolving frame 145

surrounding said sleeve, and the heater cam operated by said revolving frame, substantially as described.

17. In a braiding machine, in combination, the pivoted switches and means to operate them, the vertically swinging projecting carriers carried by said switches and means for swinging said projectors, substantially as described.

18. In a braiding machine, in combination, a plurality of spindles, a supporting flange or collar on each spindle, a guide for said spindles on an independent guiding collar in peripheral contact with said guide and a latch engaging 16 stem below the supporting and guiding column, substantially as described.

19. In a braiding machine, in combination, a plurality of spindles, a supporting flange or collar on each spindle a guide for said spindles in an independent guiding collar in peripheral contact with said flange, substantially as described.

20. In a braiding machine, in combination, a plurality of

spindles, a supporting flange or collar on each spindle, a guide for said spindles on an independent guiding collar in peripheral contact with said guide and a latch engaging 16 stem below the supporting and guiding column, substantially as described.

In testimony whereof I affix my signature, in presence of two witnesses,

ALFRED ATTENBOROUGH.
